ABSTRACT: A quick-opening process vessel with a novel, overcenter, toggle-type closure assembly wherein a very high mechanical advantage is achieved in compressing the vessel into closed and sealed position utilizing locking grooves on each end cap of the vessel. The toggle lever comprises a display surface especially desirable for use with transparent vessels. Moreover, the toggle lever utilized on ultrafiltration cells, wherein it modifies the rate of compression obtained during the edge-sealing of the membranes, has the particular advantage of assuring that the membrane is subjected to minimum strain as it is subjected to the maximum compressive sealing pressure.

FIG. 1.

FIG. 2.

FIG. 3.

HERBERT H. LOEFFLER
INVENTOR.

FIG. 4.

QUICK-CLAMPING CELL

BACKGROUND OF THE INVENTION

In the manufacture of closed, process vessels for use in processing liquids and other chemicals, it has been the practice to use a plurality of bolt-type fasteners to achieve a suitable sealing of the vessels. Some problems associated with the use of process vessels are (1) difficulty in cleaning, (2) high time-consumption in opening or closing, (3) difficulty in obtaining a uniform seal around the perimeter of the vessel, and (4) presentation of a relatively unsightly object on a laboratory bench. Nevertheless, there have been no wholly satisfactory substitutes for these prior art devices and they are still widely used in both laboratory and large-scale operations.

Moreover, when transparent process vessels are used to follow visual monitoring of the reactants, prior art devices do not provide a convenient display surface for the display of operating instructions, suppliers's name, or the like. This is a particular problem when the vessel is utilized as an ultrafiltration cell wherein careful attention must be given to the liquid level by an attendant who may be charged with watching a number of such cells.

SUMMARY OF THE INVENTION

Therefore, it is an object of the invention to provide a quick-opening process vessel which has relatively few parts and is easily and rapidly taken apart for cleaning.

Another object of the invention is to provide such a vessel which is adequately sealed for accomodating moderate operating pressures therewithin.

Another object of the invention is to provide an improved closure assembly for use with such quick-opening process vessels.

Still another object of the invention is to provide a transparent vessel which has a convenient display surface associated with the closing mechanism thereof.

Another object of the invention is to provide a closure which assures the optimum mechanical advantage will be applied to closing an ultrafiltration cell at precisely the time in the closing cycle that such advantage is required, yet with minimum strain exerted on the membrane being sealed.

Other objects of the invention will be obvious to those skilled in the art on reading this specification.

The above objects have been substantially achieved by the construction of a quick-opening vessel wherein a cylindrical reservoir is resiliently held between two end caps which end caps have positioning means such as grooves or slots therein for receiving a novel closure assembly. This closure assembly comprises a lower closure member for engaging a positioning slot in the lower end cap, and a toggle lever which is adapted for engagement with a locking groove in the upper-cap member. The toggle lever is pivotally connected to side bars which join the aforesaid lower member and toggle lever at a point proximate the bottom of the toggle lever. Stop means is provided for limiting the movement of the lever at the over-center position required to maintain the compression on the cylinder.

At least one end cap is removable from the cylinder, although for many applications each end cap may be made removable. A compressible sealing means such as an O-ring is preferably utilized to effect a seal between a removable end cap and the wall of the cylinder. The overcenter-type toggle action exerted by the closing lever is particularly advantageous with respect to obtaining the optimum compressive seal between the end caps and cylinder, because the toggle action is designed to give maximum mechanical advantage at the time maximum compression on the seal is reached. This advantage is achieved and tends to infinity as the horizontal movement of the toggle lever becomes predominant during the locking action. This action is particularly advantageous when utilized with ultrafiltration cells because it assures that membranes being edge-sealed by the higher compressive forces will be subjected to minimum strain as the sealing action is completed.

One important use of the apparatus of the invention is with ultrafiltration cells wherein it is highly desirable that the process be visible to the operator. In such apparatus the toggle lever may form a broad planar surface suitable for display of instructional or promotional material without the need of placing vision-blocking labels on the cylinder itself. Moreover, when the apparatus of the invention is used as an ultrafiltration cell, the ultrafiltration membrane is normally protected from being cut during the compressive sealing action by the low strain rate used to achieve the final sealing of the membrane by an O-ring sealing means encircling the edge thereof.

ILLUSTRATIVE EXAMPLE OF THE INVENTION

FIG. 1 is a view partially in section of the quick-clamping cell of the invention.

FIG. 2 is a view of the cell shown in FIG. 1 but taken at 90° angle therefrom.

FIG. 3 is a plan view of the quick-clamping cell of the invention.

FIG. 4 shows detail of the pivot.

Referring to FIGS. 1 and 2, it is seen that quick-clamping processing vessel 10 comprises a transparent reservoir 12 formed of a cylinder 13, an upper end cap member 14, a lower end cap member 16, each of said end caps being separated from said reservoir 12 by seal means comprised of resilient elastomeric O-rings 18.

Upper end cap 14 comprises means to receive a pressure relief valve 20 and means to hold an agitator shaft 22. A magnetic stirring bar 24 is rotably mounted on shaft 22, by bracket 26, for actuation by a magnetic stirring table (not shown) of the type known in the art. Upper cap member 14 includes a stop means 28 comprised of an inclined support wall 30 and also includes a locking groove 32 at the bottom terminal of wall 30.

Lower cap member 16 comprises a block 33 into which has been cut a positioning slot 34 thereby forming means to position a lower horizontal member 37 of a unitary, U-shaped clamp 38 of a closure assembly 39. The elongated side bars of clamp 38 comprise apertures 42 into which studs 44 of toggle lever 46 are pivotally positioned proximate the bottom of the toggle lever. Studs 44 have a rounded surface 45 to facilitate the pivoted movement of the studs in apertures 43. Toggle lever 46 comprises a planar display surface 48 and forms means for moving closure assembly from a closed tight position to an open or loose position.

By pulling outwardly on toggle lever 46, closure assembly 38 may be readily removed from the vessel. The assembly remains in one piece and thus may be readily replaced by simply bearing up upon toggle lever 46 to lock it into groove 32. Each of the end caps 14 and 16 and reservoir 12 may be individually washed, yet quickly reassembled into an operable unit utilizing closure assembly 39.

Sealed between lower O-rings 18 and bottom end cap 16 is an ultrafiltration membrane 50, e.g. a membrane of the type sold by Amicon Corporation under the trade designation XM-50. The compression on the membrane by cylinder 13's bearing on lower O-ring 18 seals the edges of the membrane against lower end-cap member 16. End cap 16 comprises a groove 52 therein and a conduit 54 therethrough which groove and conduit allow ultrafiltrate to be discharged through discharge line 56. Most ultrafiltration membranes will have a relatively porous backing member which allows the ultrafiltrate to seek the groove 52 without the aid of an intervening porous plate member. However, such a plate member may be used where the membrane itself comprises no such porous backing member or is too fragile to be self-supporting.

When the end caps are fabricated of relatively low modulus materials (e.g. from thermoplastics such as nylon, the polyaldehyde sold under the trade designation Delrin by E. I. DuPont de Nemours and Co., Inc., polytetrafluoroethylene, and the like), a particular safety feature can be built into the apparatus inasmuch as such materials will deflect enough under moderately high pressures, say 150 to 200 p.s.i.g., to break the

O-ring seal and allow escape of gas from the apparatus. Plastic materials with moduli below about 450,000 p.s.i. (ASTM D638) are most advantageous when such a "built-in relief valve" feature is desired.

I claim:

1. A quick-opening processing vessel comprising a cylinder; an upper cap member and a lower cap member, each said cap member being held in snug relationship to said cylinder by a closure assembly adapted for engagement with a locking groove in said upper cap member and a positioning slot in said lower cap member; said closure assembly comprising a lower member engaging said positioning slot, a toggle lever engaging said locking groove, side bars connection corresponding sides of said lower member and said toggle lever, said connection between said side bars and said toggle lever being a pivotal connection proximate one end of said toggle lever whereby said closure assembly may be actuated by toggle action to maintain said pressure vessel in a closed position or to loosen to allow disassembly of said pressure vessel; and stop means mounted adjacent said clamping lever to provide means for limiting its movement beyond that required to maintain said

vessel in a closed position.

2. A vessel as defined in claim 1 wherein said cylinder is transparent cylinder and wherein said toggle lever comprises a planar surface suitable for display of descriptive material.

5 3. A vessel as defined in claim 1 wherein resilient, elastomeric O-ring seal members are compressed between said cylinder and each of said cap members which members are fabricated from a relatively-low modulus material, thereby providing a built-in, over-pressure release means.

10 4. A vessel as defined in claim 1 wherein said lower cap comprises a conduit therein which provides means for removing liquid from said reservoir.

5. A vessel as defined in claim 3 comprising a semipermeable membrane positioned between said O-ring seal members

15 6. A vessel as defined in claim 1 wherein said stop means is an integral part of said upper cap member.

7. A vessel as defined in claim 1 wherein said lower member and said side members are formed of a single U-shaped element.
